UNITED STATES PATENT OFFICE.

AUGUST ZEH, OF MUNICH, GERMANY.

CEILING AND THE LIKE.

1,012,499.

Specification of Letters Patent. Patented Dec. 19, 1911.

Application filed October 6, 1910. Serial No. 585,587.

To all whom it may concern:

Be it known that I, AUGUST ZEH, a citizen of Germany, residing at Munich, Kingdom of Bavaria, German Empire, have invented 5 certain new and useful Improvements in Ceilings and the Like; and I do hereby declare the following to be a full, clear, and exact description of the invention, such as will enable others skilled in the art to which

10 it appertains to make and use the same.

My invention relates to improvements in ceilings and the like, and the object thereof is to provide a ceiling of such construction that the acoustic properties of any inclosure 15 of which the ceiling forms part will be enhanced, and provision made for deflecting sound waves, emanating from any particular part of the inclosure, to any other desired point or points in such inclosure.

20 The invention is of especial utility in auditoriums, lecture halls, and theaters, and to clearly show the application of the invention, I have illustrated the same, in the accompanying drawing, in connection with 25 a theater.

In the drawing Figure 1 is a vertical sectional view of a theater having my invention embodied in the ceiling thereof; Fig. 2 is a cross sectional view of a part of the 30 ceiling; and Fig. 3 is a plan view of the ceiling.

The arrangement and construction of the seats of the theater form no part of my present invention and will only be briefly referred to. As usual the seats are arranged in banks or tiers, *c*, *d*, *e*, there being provided the exits *f*, doorways or openings *g*, rooms or compartments *h*, the several stairways *k*, and the guard rails *t* on each floor.

The stage of the theater is designated at *s* and adjacent thereto is the space *o* for the orchestra, this space containing a wooden pit or casing surrounded by a second wooden casing *q*, a hollow space *p* being left between the wooden casings and the latter being connected by suitable bridges *r*.

I will now proceed to describe in detail the special means employed by me for deflecting the sound waves emanating from the stage and orchestra pit, to any desired parts of the house and thus increasing its acoustic properties. To this end the ceiling is formed flat or slightly curved, and is provided with a plurality of preferably radial channels or grooves *m*, which begin at a point opposite the stage *s* extend about two thirds the length of the ceiling, and finally terminate in short inclined planes *n*. The channels or grooves *m* are preferably elliptical or semicircular in cross section so that their lateral walls will deflect the sound waves laterally, while the planes *n* which may be arranged over different banks of seats, deflect the sound waves downwardly as shown by dotted lines in Fig. 1.

What I claim as my invention and desire to secure by Letters Patent, is:

As a new article of manufacture, a ceiling for the purpose set forth, having therein a series of substantially semicircular longitudinal grooves each merging into a short inclined plane.

In testimony whereof I hereunto affix my signature in the presence of two witnesses.

AUGUST ZEH.
